United States Patent Office

Des. 218,874
Patented Sept. 29, 1970

218,874

MUSIC PAGE HOLDER OR SIMILAR ARTICLE

Billie Neal Whittaker, Roy, Utah
(Rte. 3, Lawrenceville, Ill. 62439)

Filed Aug. 4, 1969, Ser. No. 18,538

Term of patent 14 years

Int. Cl. D19—99

U.S. Cl. D97—2

FIG. 1

FIG. 2

FIG. 1 is a front perspective view of a music page holder or similar article embodying my new design; and FIG. 2 is a rear perspective view thereof.

I claim:

The ornamental design for a music page holder or similar article, substantially as shown.
